UNITED STATES PATENT OFFICE.

LOUIS E. SADLER, OF ATTLEBOROUGH, MASSACHUSETTS, ASSIGNOR TO
F. H. SADLER & CO., OF SAME PLACE.

ORNAMENTAL RING.

SPECIFICATION forming part of Letters Patent No. 611,004, dated September 20, 1898.

Application filed January 20, 1898. Serial No. 667,211. (No model.)

To all whom it may concern:

Be it known that I, LOUIS E. SADLER, of Attleborough, in the county of Bristol and State of Massachusetts, have invented a new and useful Improvement in Ornamental Rings; and I hereby declare that the following is a full, clear, and exact description of the same, reference being had to the accompanying drawings, forming part of this specification.

10 This invention has reference to an improvement in ornamental finger-rings; and it consists in the peculiar and novel construction, as will be more fully set forth hereinafter.

In the manufacture of ornamental finger-rings as heretofore practiced the blank for the ornamental hoop was struck up in a suitable die to produce the ornamental center. It was then bent up into the form of a hoop and the ends were soldered together to form 20 the ring. Rings constructed in this manner wear out very rapidly near the soldered joint, because the adjacent metal is softened by the heat used in soldering the two ends together. The jewel-settings have heretofore been secured to the ornamented portion of the ring by solder and the heat used to secure the 25 same softened this portion of the rings.

The object of this invention is to overcome these objections and produce an ornamental 30 ring the metal of all parts of which is hard and durable. To secure this end, I form a suitable drawn wire into a hoop and secure the ends together by solder to form the ring. I now ornament the joint portion of the ring 35 by stamping this part in suitable dies and form the ornamented part of the ring at the jointed part, thereby restoring the hardness drawn from the metal by soldering by the blow of the dies. I also draw up from the 40 metal of the ring a tubular thimble or thimbles and secure the jewel setting or settings to the ring by rolling the end of the thimble over the base of the setting, as will be more fully set forth hereinafter.

45 Figure 1 is an edge view of the plain ring. Fig. 2 is a side view of the same, showing the soldered joint near the upper portion. Fig. 3 is a top view of the stamped ornamented portion of the ring. Fig. 4 is a side view of 50 the same. Fig. 5 is a top view of the ornamented center of the ring, showing the tubular

thimble drawn up from the metal of the ring. Fig. 6 is a side view of the same. Fig. 7 is a top view of the ornamented center of the ring provided with a jewel-setting. Fig. 8 is a side view of the same; and Fig. 9, an enlarged sectional view of the ornamented center, showing the jewel-setting secured to the same by the rolling over of the end of the thimble.

55 In the drawings, *a* indicates the wire, of suitable cross-section, of which the ring is made. This wire is formed into a hoop, the ends of which are secured together by solder. The abutting joint *b* may extend at right angles across the wire of the ring or be made in 60 65 any other usual form.

The heat used in soldering the joint draws the temper of the adjacent metal, and to restore this temper or hardness the soldered portion of the ring is subjected to the blow of 70 the dies in forming the ornamented parts *c c* of the ring, whereby the temper or hardness of the metal is restored.

75 When the ring is to be provided with set jewels, a flat portion *d* is formed by the dies for the setting of the jewels. In the drawings a ring provided with one central jewel-setting is shown to illustrate the invention, but two or more jewels may be set into a ring. To secure the jewel-setting without the use of 80 solder or heat, so as to retain the temper or hardness of the metal, I draw up in suitable dies the tubular thimble *e* from the metal of the ring and pierce the base *g* of the setting *f*. The base *g* is now passed over the thimble *e*, the upper edge of which is expanded over the base to firmly secure the setting, as 85 is shown in Fig. 9. By this construction the temper or hardness of the metal of all portions of the ring is preserved.

90 The ring is much more durable, as the hard metal resists wear and the soldered joint is materially strengthened, because by the flow of the metal in stamping the ornamental portion of the ring the soldered joint *b* is extended into approximately the direction shown in Fig. 9.

95 Having thus described my invention, I claim as new and desire to secure by Letters Patent—

100 1. A ring formed of wire the ends of which are secured together by solder, and the jointed

portion ornamented by dies; whereby the jointed portion of the ring is hardened by the dies as described.

2. In a ring, the combination with the wire 5 *a*, the soldered joint *b*, and the ornamented center *c*, *c*, of the jewel-setting *f*, the perforated base *g*, of the setting and the tubular thimble *e* integral with the ring; whereby the setting is secured to the ring by the expansion

of the end of the thimble without heating the 10 metal, as described.

In witness whereof I have hereunto set my hand.

LOUIS E. SADLER.
